CARL JOHN HAGSTROM, OF GLEN COVE, NEW YORK.

ANTIRATTLE-CATCH.

1,344,508.

Specification of Letters Patent. Patented June 22, 1920.

Application filed June 14, 1919. Serial No. 304,119.

To all whom it may concern:

Be it known that I, CARL JOHN HAGSTROM, a citizen of the United States, and a resident of Glen Cove, in the county of Nassau and

5 State of New York, have invented a new and Improved Antirattle-Catch, of which the following is a full, clear, and exact description.

This invention relates to builders' hardware and has particular reference to catches for swinging members such as windows, doors or the like.

Among the objects of the invention is to provide a catch for use on swinging doors or 15 analogous devices having the function of automatically causing the temporary holding engagement between the relatively movable and stationary parts such as the striking edge of a door and its jamb or frame.

20 Another object of the invention is to provide a catch having as its principal movable member a bolt pivoted between its ends to a part which carries it, said bolt having a point engageable with a socket piece carried 25 by the other part and serving always to cause the bolt to swing on its pivot while a spring acts upon the opposite end of the bolt from its point for the purpose of holding the bolt either in its locking position or at 30 any other desired position according to the co-operative relation between the socket piece and the bolt.

More definitely stated, assuming that the bolt is carried by the door, or its equivalent, 35 when the door is opened the keeper will cause the bolt to swing on its pivot to the extent corresponding to the space between the striking edge of the door and the socket piece while the spring acts to hold the bolt 40 with its point in precisely the position occupied by it when it swings with the door away from the socket piece so that when the door is again swung shut said point of the bolt will pass freely past the outer portion 45 of the socket piece and strike against a lip projecting inward toward the door from the main portion of the socket piece so that the closing of the door will automatically cause the bolt to swing into holding position.

50 This device is especially designed for use in connection with doors for cupboards, refrigerators, bookcases, or the like.

With the foregoing and other objects in view the invention consists in the arrangement and combination of parts hereinafter described and claimed, and while the inven-

tion is not restricted to the exact details of construction disclosed or suggestion herein, still for the purpose of illustrating a practical embodiment thereof reference is had to 60 the accompanying drawings, in which like reference characters designate the same parts in the several views, and in which—

Figure 1 is an outside perspective view of the main portion of the catch comprising a 65 casing and bolt.

Fig. 2 is a perspective view of the socket piece.

Fig. 3 is a horizontal sectional detail showing the action of the catch while the 70 door is swinging shut.

Fig. 4 is a similar view showing the action while the door is swinging open.

Fig. 5 is a view indicating the operation of the catch holding the door shut; and 75

Fig. 6 is a detail perspective view corresponding to Fig. 1 but showing a different form of casing.

While I show the casing and bolt carried by the movable member or door and the 80 socket piece fixed to the jamb or frame, it is to be understood that this arrangement of the parts may be reversed if desired.

As shown in Fig. 1 the casing comprises two side pieces 10 connected by a cross bar 85 11 at their inner ends and by a face plate 12 at their outer ends, said face plate having holes 12' for screws for securing the body of the casing in a mortise 13 in the striking edge of the door. The face plate 12 is countersunk preferably flush with said striking edge.

The bolt 14 is in the nature of a lever of the first class pivoted between the side pieces 10 on a pivot 15, while the active end 95 or point 16 of the bolt projects beyond the striking edge of the door into or through a notch 17 formed in the face plate 12. The inner end of the bolt is rounded at 18 concentric with the pivot and is adapted to bear 100 against a leaf spring 19 arranged between the side plates 10 and having one end thereof anchored by means of a screw 20 to the bar 11. The face of the bar 11 against which the end of the spring is anchored by 105 the screw 20 is preferably beveled at 11' so that the tension of the spring may be increased or reduced by turning the screw tighter or looser, access being had to the screw through a hole 21 formed through the 110 door. The free end of the spring 19 adjacent to the rounded end 18 of the bolt is

adapted to bear flatly against a flat face 22 of the bolt when the door is shut whereby the tension or force of the spring tends to hold the bolt in the position shown in Fig. 5 or substantially parallel to the plane of the door. When, however, the bolt is swung around its pivot through an angle of at least about 40 degrees said free end of the spring will bear against the rounded end 18 which 10 being concentric with the pivot will always hold the bolt at the angle at which it may be turned.

Figs. 3, 4 and 5 show the tendency of the doors to shrink away from the jambs 15 rendering ordinary catches ineffective or useless. This catch, however, operates just the same irrespective of the reasonable distance of the striking edge of the door from the jamb. Obviously if the door were not 20 spaced so much from the jamb as indicated in the drawings the bolt would be turned in the opening movement of the door through a greater angle than that indicated, but it would still be retained by the spring at the 25 angle to which it is turned by the wiping of the flat face of the bolt against the contact portion 23 of the socket piece 24.

Said socket piece is essentially a flat piece of metal stamped or otherwise formed with 30 a hole 25 in its center into which the point of the bolt is adapted to be projected when the door swings shut, said point striking against the projecting lip 26 bent laterally from the plane of the socket piece toward 35 the door. Said socket piece may be countersunk or set flush into the jamb so as to provide for the closing of a close fitting door. Fig. 3 indicates the closing action of the door and the point of the bolt striking 40 against the lip 26 which will cause the turning of the bolt around its pivot 15 so as to cause the spring to bear against the flat face of the bolt as shown in Fig. 5. Obviously the door may be pulled open by pulling 45 on a knob or the like, not shown, and this opening movement will be resisted only by the force of the spring 19 acting against the flat face of the bolt. This force may be overcome by a pull on the door and when 50 the door is so pulled open the point portion of the bolt will wipe against the contact portion 23 and cause the turning of the bolt around its pivot as shown in Fig. 5. The spring will not act to cause the 55 turning of the bolt while the door is open, the bolt remaining stationary in the position caused to be assumed by it when the door is opened. The spring acts only as a snap upon the bolt after the bolt is turned 60 toward its position parallel to the door when closing.

By tightening the screw 20 causing the anchored end of the spring to hug more tightly against the bar 10, the force of the

spring will be increased and so the tendency 65 to rattle will be reduced. In other words as will be plainly seen from Fig. 5 with the screw tightened the force of the spring will act to hold the point of the bolt more firmly against the part 23 of the socket 70 piece. This socket piece may be secured in the door jamb by any suitable fastening devices passed through the holes 24.

In Fig. 6 the casing 27 is shown as of cylindrical nature rather than rectangular 75 as in Fig. 1, otherwise the structure and operation are the same as already described.

I claim:

1. The herein described anti-rattle catch for doors or the like comprising a casing 80 and socket piece connected to the relatively movable parts, a bolt pivoted in the casing and having an end projecting beyond the same, a spring acting upon the inner end of the bolt, said end being rounded whereby 85 the force of the spring thereagainst while the door is being opened will serve to hold the bolt in any one of many various positions according to the space between the door and the jamb, and means carried by the 90 socket piece against which the projecting end of the bolt is adapted to strike when the door is closing to cause the bolt to be turned into holding position.

2. In a door catch of the class set forth, a 95 socket piece having an opening therein and a lip adjacent to the opening and projecting laterally therefrom, a casing, a bolt pivoted between its ends within the casing, one end of the bolt projecting beyond the casing and 100 adapted to strike against said lip for turning the bolt into said opening into holding position, and a spring bearing frictionally against the opposite end of the bolt and serving to hold the bolt in any one of many 105 intermediate positions according to the space between the striking edge of the door and the jamb, and to resiliently hold the bolt in its holding or locking position.

3. In a door catch, the combination of a 110 casing, a bolt pivoted between its ends in the casing and having one end projecting beyond the same, said bolt having a rounded end and a flat surface leading therefrom toward its opposite end, a flat spring within 115 the casing adapted to bear against said rounded end and flat surface, means to anchor the spring to the casing providing for the variation in tension thereof, and means coöperating with said casing and bolt to 120 cause the bolt to automatically move into locking position when the door is being closed.

4. In a door catch, the combination of a 125 casing adapted to be mortised in the striking edge of the door, a socket piece adapted to be fixed to the door jamb, said socket piece having a lip projecting toward the

door, a bolt pivoted within the casing and having one end projecting well beyond the casing for coöperation with the socket piece lip irrespective of the distance between the 5 door and the jamb, and a spring acting frictionally while the door is being opened to hold the bolt in any angle at which it may be

left automatically by contact with the socket piece while the door is being opened and acting upon the bolt to hold it substantially 10 parallel to the door in locking position when the door is closed.

CARL JOHN HAGSTROM.
